HEATING PAD

Carlos W. Veach, 3921 Ashcraft,
Los Angeles 48, Calif.
Filed Sept. 29, 1961, Ser. No. 141,825
3 Claims. (Cl. 128—399)

The present invention relates to heating pads, and more particularly, to electrically powered heating pads that are adapted to be worn on or attached directly to the skin of a person.

It is frequently desirable to apply heat in localized areas to the surface of a person's skin. More particularly, it may be desirable to apply heat to an extremity such as a hand or a foot to assist the body in maintaining a normal temperature therein or to apply heat to a diseased or infected area to assist in the recovery from a disease or infection. In the latter cases, it may also be desirable to apply suitable medicaments to the skin surface at the same time that the heat is being applied thereto. In order to accomplish these objectives, numerous attempts have been made to provide a device that can be placed on the skin for applying heat to the surface thereof. Although such devices have proved to be successful in applying heat to the skin, they have numerous objections. For example, in devices such as a hot water bottle wherein a container is filled with a hot liquid or exothermic chemicals, they are bulky and/or uncomfortable and require frequent attention to maintain proper control of the temperature. As a result, devices of this nature have generally only been useful on a person who is in a reclining or sitting position. In so-called electric heating pads, heating elements are provided for generating the required heat. However, the source of power has heretofore had to be of a substantial nature such as a 110 volt power line. Heating pads of this nature are reasonably compact and can have the temperature thereof closely controlled. However, since relatively high voltages are employed, the dangers from electrical shock are substantial and it is necessary to employ large amounts of insulation to separate the heating elements from the skin of the person employing the heating pad. In addition, when an electric heating pad is to be employed with a liquid medicament that is electrically conductive, the dangers from the high voltage are greatly increased and accordingly necessitate the use of water-proofing covers, etc. As a result, the foregoing heating pads have been unsuitable for applying heat to localized areas to the human body when the person is engaged in normal activities and particularly in certain types of locations such as between a person's legs, inside of a splint, etc.

It is, therefore, an object of the present invention to provide a heating pad for use on the human body which will overcome the foregoing difficulties.

It is an object to provide a heating pad that is not only more compact and easier to use, but will also be more efficient and effective in operation.

It is an object to provide an electrical heating pad that may be employed in any desired location such as inside of a splint or other inconvenient locations.

It is also an object to provide a heating pad that may be employed while the person is carrying on normal activities. More particularly, this is to be accomplished by providing a strip of flexible material that is arranged to form a backing member that may be secured to the surface of a person's skin. One or more electrically conductive heating elements may then be secured to the face of the backing member so that when the backing member is secured in position on the skin, the heating elements will be in direct intimate contact with the skin. This will greatly increase the rate of heat transfer into

2

the skin. This will in turn drastically reduce the amount of power required to maintain a given temperature to the point where it may be economically obtained from a battery worn or carried by the patient. The heating elements preferably comprise one or more conductive wires having a low resistance. As a result, for any given power requirement the voltage drop across the heating elements may be made so low, for example, five volts or less, that the danger of electrical shock is eliminated. As a consequence, the insulation may be eliminated and the heating elements placed in direct contact with the surface of the skin. In addition, if desired, any suitable liquids or medicaments may be applied to the skin and/or in the immediate vicinity of the heating elements without in any way increasing the likelihood of electrical shock.

These and other features and advantages of the present invention will become readily apparent from the following detailed description thereof particularly when taken in connection with the accompanying drawings wherein like numerals refer to like parts and wherein:

FIGURE 1 is a top plan view of a heating pad embodying the present invention;

FIGURE 2 is a bottom plan view of the heating pad in FIGURE 1;

FIGURE 3 is a longitudinal cross sectional view taken substantially along the plane of line 3—3 in FIGURE 1 and looking in the direction of the arrows thereon and showing the heating pad secured to the surface of a layer of skin;

FIGURE 4 is a top plan view of a heating pad embodying a modified form of the present invention;

FIGURE 5 is a longitudinal cross sectional view of the heating pad of FIGURE 4 taken substantially along the plane of line 5—5 in FIGURE 4 and looking in the direction of the arrows thereon; and

FIGURE 6 is a schematic diagram showing the heating pad operatively interconnected with an alternative source of power.

Referring to the drawings in more detail and particularly to FIGURES 1, 2 and 3, the present invention is particularly adapted to be embodied in a heating pad 10 that may be mounted on the surface 12 of a layer of skin on the human body. In the present instance, this heating pad 10 comprises a backing member 14 which may be formed from a strip of suitable material. The material is preferably relatively flexible so as to be capable of always conforming to the distortions of the skin while adhering thereto. For example, it may comprise a piece of plastic, cloth or similar material and it may or may not be porous. The backing member 14 which will define the size and shape of the heating pad 10, may be of any desired size and shape suitable for the use to which it is to be put. Preferably the backing member 14 is approximately equal to or slightly larger than the area which it is intended to heat.

The heating pad 10 may be secured in position by any suitable means such as employing a strip of adhesive tape etc. However, in the present instance an opening 16 is provided in each end of the pad 10. This opening 16 is formed by a hollow rivet 18 that extends completely through the backing member 14 and has the opposite ends thereof headed to thereby form eyelets. Thus, an elastic band or similar device having hooks on the ends thereof may be attached to the rivets 18 and extend around the body member to thereby secure the pad 10 in position. In addition, or alternatively, a layer 20 of pressure sensitive adhesive may be formed on the inner surface of the backing member 14. Thus, when the heating pad 10 is in operative position, the layer 20 of adhesive will be in engagement with the surface 12 of the skin and accordingly will retain the pad 10 in position thereon.

In order to generate the required heat for maintaining the required temperature in the skin, one or more heating elements 22 may be provided on the backing member 14. The heating elements 22 are preferably disposed on the inner surface of the backing member 14 whereby they may be disposed in direct intimate contact with the surface 12 of the skin. In the present instance, the heating element 22 comprises a conductive wire 24 which is formed into a suitable pattern such as a series of undulations. The wire 24 may be secured in position by any suitable means such as dry adhesive bonding. However, in the present instance, the wire 24 is merely compressed into the layer 20 of pressure sensitive adhesive on the inner surface of the backing member 14 so as to be permanently secured thereto. The opposite ends 23 of the wire 24 forming the heating element 22 may extend through the backing member 14 and thereby form means suitable for interconnecting with a suitable source of power. Although any suitable connector means may be provided, in this embodiment a pair of suitable snap fasteners 26 or similar devices are secured to the backing member 14 so that the ends 23 of the wire 24 may be secured thereto. The fasteners 26 are in turn adapted to be interconnected with a suitable source of power such as a battery 25.

Although the heating elements 22 may be formed in any suitable manner, in the present instance they comprise a wire 24. The wire 24 which may consist of any suitable electrically conductive materials preferably of copper or a similar material having a low specific resistivity. Thus, even though the length of the wire 24 may be long enough to insure the heating element covering substantially the entire area of the heating pad 10, the overall resistance of the heating element 22 will be relatively low, for example, on the order of a few ohms. Since the amount of power provided by a heating element is determined by the square of the voltage drop thereacross divided by the resistance thereof, it will be readily apparent that by employing a small resistance a small voltage may be employed. For example, with a resistance on the order of 2 to 4 ohms and a voltage of about 5 volts, a power output of from about 5 watts to about 15 watts may be obtained. It is, of course, readily apparent that such a low voltage is below the critical level that produces electrical shock or burning and accordingly the heating elements may be in direct contact with the surface 12 of the skin. As a consequence, the heat transfer from the heating element 22 into the skin will be very efficient. Thus, a small number of watts will be adequate to maintain the temperature of small areas. It may, therefore, be seen that it is now possible to employ a relatively small battery 25 for energizing the heating pad 10 for extended periods. This will in turn permit a person to carry on normal activities while utilizing the present heating pad 10.

As an alternative, the heating pad 28 of FIGURES 4 to 6 inclusive may be employed. In this embodiment a backing member 30 is provided which has a size and shape corresponding to the area that is to be heated. The backing member 30 may consist of any suitable material; however, it is preferably a cloth or similar material that is sufficiently porous to permit moisture to pass therethrough.

In order to secure the heating pad 28 in position, the opposite ends of the backing member 30 may be provided with eyelets 32 that are formed by hollow rivets 34. These eyelets 32 may be adapted to receive suitable hook fastening means on the opposite ends of an elastic band that extends around a body member. In addition, or alternatively, a layer of pressure sensitive adhesive may be provided on the inner surface of the backing member 30 so as to engage the surface of the skin and adhere thereto and thereby secure the pad 28 in position.

An absorbent pad 36 consisting of a material such as cotton batting, gauze, etc. may be provided on the backing member 30. In addition, an outer cover 38 may extend the full length of the backing member 30. The op-

posite ends of the cover 38 are secured on the backing member 30 by any suitable means such as bonding or by the rivets 34. It may thus be seen that the pad 36 will be secured in position between the cover 38 and the backing member 30.

In order to generate the required heat, one or more heating elements 40 similar to the heating elements 22 in the first heating pad 10 may be provided on the surface of the backing member 30. In the present instance, this heating element 40 comprises a conductive wire 42 which is formed into an undulating pattern and is secured thereto by any suitable means such as an adhesive. The wire 42 may consist of any suitable material, however, it preferably comprises a material having a low specific resistivity such as copper. Thus, the overall resistance of the heating element 40 will be relatively low, for example, on the order of a few ohms. The opposite ends 43 of the wire 42 forming the heating element 40 preferably extend through the backing member 30 and terminate with connector means 45 which are adapted to be interconnected with a suitable power source. In the present instance the wire 42 terminates in the form of a couple of connector pins 44. These pins 44 are in turn adapted to plug into a pair of sockets 46 interconnected with the secondary of a step down transformer 48.

Since the overall resistance of the heating element 40 will be very low, the voltage drop thereacross will also be very small. As a consequence, the heating element may be placed in direct contact with the surface of the skin without any danger of electrical shock or execution occurring therefrom. In addition, if so desired, a liquid such as plain water or a solution containing a suitable medicament may be absorbed in the pad 36. This liquid may then traverse the porous backing member 30 and cause the heat being applied to the skin to be accompanied by a suitable moisture. It is, of course, readily apparent that even though the moisture increases the electrical conductivity on the skin surface, the voltage will be so low that there is still no danger of an electrical shock or burn.

It may thus be seen that a heating pad has been provided that is very compact and may be used in any desired location on the human body. More particularly, it may be used inside of a bandage or cast without in any way interfering with the operation thereof. Since the power supply has a voltage that is below the critical level that produces shock or burning, there is no danger from such injuries even though there is little or no insulation between the heating element and the skin. In addition, since the heating elements are disposed to insure a more efficient heat transfer, they may be energized by means of batteries whereby the heating pad may be employed for heating areas even while the wearer is engaged in normal activities. Although only a limited number of embodiments and applications have been disclosed, it will be readily apparent to those skilled in the art that numerous changes and modifications may be made thereto without departing from the spirit of the invention. Accordingly, the foregoing description and drawings are for illustrative purposes only and are not intended to limit the invention which is defined only by the claims which follow.

What is claimed is:

1. Means for electrically supplying a predetermined amount of heat directly to a limited area on the external surface of a layer of skin, said means comprising the combination of:
  - a strip of flexible material arranged to form a backing member having a length and width that correspond to said area, said strip being adapted to be positioned on said skin with a surface thereof disposed in intimate contact with said external surface of said skin, means on said backing member for retaining said member positioned on said layer of skin with the surface thereof forced against said external surface so as to

- be maintained in substantially direct contact therewith,
- an electrical heating element consisting of an electrically conductive wire having a low specific resistance that will provide an overall resistance of said heating element that is low enough to permit the predetermined amount of heat to be generated upon the application of a voltage across said element that is below the critical value for producing an electrical shock or burning of said skin,
- adhesive means on said backing member for maintaining in a predetermined pattern with at least a portion of said element being exposed for disposition in direct intimate contact with the surface of said skin when said backing member is disposed thereon, and
- means for interconnecting said heating element with a source of electrical power having an electrical potential that is below said critical level for producing electrical shock or burning of said skin.
2. Means for electrically supplying a predetermined amount of heat directly to a limited area on the external surface of a layer of skin of a person, said means comprising the combination of:
- a strip of flexible material arranged to form a backing member having a length and width that correspond to said area, said strip being adapted to be positioned on said skin of said person with a surface thereof disposed in intimate contact with said external surface of said skin,
- a film of pressure sensitive adhesive covering at least a portion of said surface of said backing member for being disposed on said skin surface, said film being effective for retaining said member positioned on said layer of skin in response to being forced thereagainst with said surfaces maintained in substantially direct contact with each other,
- an electrical heating element consisting of an electrically conductive wire having a low specific resistance that will provide an overall resistance of said heating element that is low enough to permit the predetermined amount of heat to be generated upon the application of a voltage across said element that is below the critical value for producing an electrical shock or burning of said skin,
- said wire being disposed in an undulating pattern on the surface of said backing member and embedded in said film of adhesive for being maintained in said film in said undulating pattern, at least a portion of said element being exposed through said film of adhesive for disposition in direct intimate contact with the surface of said skin when said backing member is disposed thereon,
- a power source for being carried by said person, and means for interconnecting said power source with said heating element for supplying electrical power thereto at an electrical potential that is below said critical level for producing electrical shock or burning of said skin.
3. Means for electrically supplying a predetermined amount of heat directly to a limited area on the external surface of a layer of skin of a person, said means comprising the combination of:
- 5 a strip of flexible porous material arranged to form a backing member having a length and width that correspond to said area, said strip being adapted to be positioned on said skin of a person with a surface thereof disposed in intimate contact with said external surface of said skin,
- 10 an absorbent pad disposed on the opposite side of said strip for maintaining said porous strip moist, a cover disposed over said pad for preventing the loss of moisture into the atmosphere,
- 15 a film of pressure sensitive adhesive on said surface of said backing member for being disposed on said skin surface, said film being effective for retaining said member positioned on said layer of skin in response to being forced thereagainst with said surfaces maintained in substantially direct contact with each other,
- 20 an electrical heating element consisting of an electrically conductive wire having a low specific resistance that will provide an overall resistance of said heating element that is low enough to permit the predetermined amount of heat to be generated upon the application of a voltage across said element that is below the critical value for producing an electrical shock or burning of said skin,
- 25 said wire being disposed in an undulating pattern on the surface of said backing member and embedded in said film of adhesive for being maintained in said film in said undulating pattern, at least a portion of said element being exposed through said film of adhesive for disposition in direct intimate contact with the surface of said skin when said backing member is disposed thereon, and
- 30 means for interconnecting said heating element with a source of electrical power having an electrical potential that is below said critical level for producing electrical shock or burning of said skin.
- 35
- 40
- 45
